UNITED STATES PATENT OFFICE.

BENJAMIN S. BERNHARD, OF BOSTON, MASSACHUSETTS.

DOOR CLOSER AND CHECK.

Application filed April 12, 1922. Serial No. 551,902.

To all whom it may concern:

Be it known that I, BENJAMIN S. BERNHARD, a citizen of the United States, and resident of Boston, in the county of Suffolk and State of Massachusetts, have invented a new and useful Door Closer and Check, of which the following is a specification.

My invention relates to means for closing and checking doors or the like and one feature thereof consists in mounting the parts so that they will be entirely invisible when the door or the like is closed.

Another feature is a flexible connecting element which is the only movable part of the device visible between the door and frame when the door is open.

Another feature is a rotary member to operate the closing and checking mechanism, said rotary member having wound upon it said flexible member.

Other features will be pointed out below.

In the drawings—

Figure 1 is a plan, partly in section, of a device embodying my invention;

Figure 2 is a front elevation of the same;

Figure 3 is an end elevation of the parts mounted in the door and looking from the left;

Figure 4 is a section on line 4—4 of Figure 2 and showing certain other parts in section;

Figure 5 is a sectional view taken on line 5—5 of Figure 1;

Figure 6 is an elevation, partly in section, showing the door closed;

Figure 7 is a section on line 7—7 of Figure 5; and

Figure 8 is a sectional detail described below.

In the drawings I show a right-handed hinged door but my invention is applicable to doors or the like which have left-handed hinged mountings or other mountings than hinged.

The door frame A is recessed to receive an anchoring member A', the outer portion of which is flush with the frame and is held by screws a and a' and has an opening a² leading to recess a³ suitably formed for universal swinging connection with member a⁴ which has connection with flexible member A² which is preferably a metal strap but might be of any suitable shape or material, the preferred connection being made by passing the end of member A² through opening a⁵ in member a⁴ and then attaching a

holding element such as rivet a⁶ seated in recess a⁷.

Embedded in the door B is a cylindrical casing B' having a plate portion b, the outer portion of which is flush with the edge of the door, said plate portion being held in position by screws b', and having a perforation b² to permit passage of member A². Bushing b³ carries thimble b⁴ which furnishes one abutment for spring B² and said thimble, and consequently the spring may be adjusted by screw b⁵. The other abutment of the spring is the piston B⁶ provided with rack B⁷ engaging pinion B⁸ on shaft B⁹, to which is pinned flanged drum B¹⁰, around which is wound the end of member A², said end being connected to said drum at B¹¹. The piston is provided with a strengthening web b¹² and with ball valves of a well-known type and conduit B¹³ leads from one end of the casing nearly to the other end, said conduit being controlled by valve B¹⁴, the head of which is in threaded engagement with a threaded recess in the casing.

The casing B' has a boss b¹⁵ having a central opening large enough to permit passage therethrough of bearing member b¹⁶ which may be then threaded into place, after which the shaft B⁹ with its pinion is put in place through said opening and then bearing member b¹⁷ is put in place, after which the drum is pinned to shaft B⁹.

The casing is preferably completely filled with suitable fluid and as the door is moved from its closed position the member a⁴ swings and the flexible member A² is unwound, rotating the drum and consequently the pinion and moves the piston to the left as in Figure 4, compressing the spring and permitting most of the fluid to flow past the balls of the ball valves and some through conduit B¹³. When the door is released the spring acts to return the piston to the original position and thereupon the fluid passes through conduit B¹³ but can not return past the balls and the drum actuated by the rack and pinion winds up member A² and thereby closes the door, the checking action being caused by the fluid passing through conduit B¹³ and controlled by valve B¹⁴ and when the door is closed as shown in Figure 6 there will be absolutely no portion of the device visible from either side of the door.

In installing my device, in case, for example, casing B' is to be mounted in the

door, I draw strap A² out and hold it by clamp D which bears against the face of plate b. The casing is then inserted in the door and held in place by screws b' and the anchorage A' is inserted in the frame and held by screws a and a' and then the clamp is removed.

As a convenient way of putting strap A² in place I provide slot b¹⁰ in plate b through 10 which member A² may be lowered into opening b².

What I claim is:

1. A device of the character described comprising a door member; a supporting member therefor; a stationary casing supported by one of said members; a piston fitting within, and cooperating with, said casing; a spring within the casing and tending normally to actuate said piston to close the 15 door, said piston forming an abutment for said spring; means within the casing and acting on said piston to check the closing action of said piston; a rotary element operatively connected with said piston to close the 20 door; and a flexible element operatively connected with said rotary element to close the door and extending substantially to and being connected with, the other of said members.

30 2. A device of the character described comprising a door member; a supporting member therefor; a stationary casing supported by one of said members; a piston fitting within, and cooperating with, said casing; a spring within the casing and tending normally to actuate said piston to close the 35 door, said piston forming an abutment for said spring; means within the casing and acting on said piston to check the closing action of said piston; a rotary element operatively connected with said piston to close the 40 door; and a flexible element operatively connected with said rotary element to close the door, said flexible element having direct 45 connection with the other of said members.

3. A device of the character described comprising a door member; a supporting member therefor; a stationary casing supported by one of said members; a piston fitting within, and cooperating with, said casing; a spring within the casing and tending normally to actuate said piston to close the 50 door, said piston forming an abutment for said spring; means within the casing and acting on said piston to check the closing action of said piston; a rotary element operatively connected with said piston to close the 55 door; and a flexible element operatively connected with said rotary element to close the door and having swinging connection with the other of said members.

4. A device of the character described comprising a door member; a supporting member therefor; a stationary casing embedded in one of said members; a piston fit-

ting within, and cooperating with, the casing; a spring within the casing and tending normally to actuate said piston to close the door, said piston forming an abutment for said spring; means within said casing and acting on said piston to check the closing action of said piston; a rotary element operatively connected with said piston to close the door; and a flexible element engaging said rotary member to close the door and having operative connection with the other of said members.

5. A device of the character described comprising a door member; a supporting member therefor; a stationary casing embedded in one of said members; a piston fitting within, and cooperating with, the casing; a spring within the casing and tending normally to actuate said piston to close the door, said piston forming an abutment for 60 said spring; means within said casing and acting on said piston to check the closing action of said piston; a rotary element operatively connected with said piston to close the door; and a flexible element engaging 65 said rotary member to close the door and having a portion extending longitudinally from said rotary element substantially to the other of said members when the door is closed, said flexible element operatively connecting said rotary element and said other of 70 said members.

6. A device of the character described comprising a door member; a supporting member therefor; a stationary casing embedded in one of said members; a piston fitting within, and cooperating with, the casing; a spring within the casing and tending normally to actuate said piston to close the door, said piston forming an abutment 100 for said spring; means within said casing and acting on said piston to check the closing action of said piston; a flexible element operatively connected to the other of said members; means operatively connecting said flexible element and said piston to close the 105 door.

7. A device of the character described comprising a door member; a supporting member therefor; a stationary casing embedded in one of said members; a piston within, and cooperating with, the casing; a spring within the casing and tending normally to actuate said piston to close the door, said piston forming an abutment for 115 said spring; means within said casing and acting on said piston to check the closing action of said piston; a flexible element operatively connected to the other of said members; and means including a rotary member operatively connecting said flexible element and said piston, said rotary member being actuated by said piston and actuating said flexible element to close the door.

8. A device of the character described 120

- comprising a door member; a supporting member therefor; a stationary casing embedded in one of said members; a piston within, and cooperating with, the casing; a spring within the casing and tending normally to actuate said piston to close the door, said piston forming an abutment for said spring; fluid means substantially filling said casing and acting to check the closing action of said piston; a flexible element operatively connected to the other of said members; and means operatively connecting said flexible element and said piston to close the door.
9. A device of the character described comprising a door member; a supporting member therefor; a stationary casing embedded in one of said members; a piston fitting within, and cooperatively engaging, said casing; a spring within said casing and tending normally to actuate said piston to close the door; means within said casing and acting on said piston to check the closing action of said piston; a rotary element operated through said piston; and a flexible element operatively connected to the other of said members and having a winding connection with said rotary element, the latter actuating the flexible element to close the door member.
10. A device of the character described comprising a door member; a supporting member therefor; a stationary casing embedded in one of said members; a piston within, and cooperatively engaging, said casing; a spring within said casing and tending normally to actuate said piston to close the door; means within said casing and acting on said piston to check the closing action of said piston; a rotary element operated through said piston; a drum mounted on said rotary element outside of said casing; and a flexible element operatively connected to the other of said members and having a winding connection with said drum, the latter actuating the flexible element to close the door member.
11. A device of the character described comprising a door member; a supporting member therefor; a stationary casing embedded in one of said members; a piston fitting within, and cooperatively engaging, said casing; a spring within said casing and tending normally to actuate said piston to close the door; means within said casing and acting on said piston to check the closing action of said piston; a rotary element operated through said piston; and a flexible element operatively connected to the other of said members and having a winding connection with said rotary element, the latter actuating the flexible element to close the door member.

BENJAMIN S. BERNHARD.
